UNITED STATES PATENT OFFICE

GILBERT H. GROVES, OF PORTLAND, OREGON

WRENCH

Application filed September 24, 1928. Serial No. 307,997.

This invention relates generally to wrenches, and particularly to ratchet wrenches.

The main object of this invention is to provide a new form of ratchet wrench in which lost motion will be almost entirely eliminated.

The second object is to construct a ratchet wrench which will be extremely easy to manufacture and unusually rugged in construction in proportion to the amount of material employed in same.

The third object is to provide a ratchet having a special means for enabling the operator to prevent reverse rotation thereof, and at the same time to make the direction in which the wrench is driving easily discernible to the eye.

These, and other objects, will become more apparent from the specification following as illustrated in the accompanying drawing, in which:

Figure 1 is a plan of the wrench with a portion broken away to show the interior. Figure 2 is a side elevation of the wrench. Figure 3 is a bottom view of the wrench showing the side opposite that shown in Figure 1. Figure 4 is a section taken along the line 4—4 in Figure 3. Figure 5 is a perspective view of the socket. Figure 6 is a perspective view of a roller. Figure 7 is a perspective view of a wrench head showing the manner of resisting reverse rotation. Figure 8 is a section taken along the line 8—8 in Figure 7.

Similar numbers of reference refer to similar parts throughout the several views.

Referring in detail to the drawing, the wrench consists of a handle 10 at one end of which is formed a head 11 having a circular opening 12 formed therein.

The faces 13 of the head 11 are straight and parallel to each other. Within the opening 12 is placed the socket member which consists of a cylindrical body 14 having a square opening 15 and projecting arms 16, whose outer portions 17 are curved and bear within the interior of the opening 12. Each of the arms 16 is provided with one straight side 18 which contains a hole 19 for a spring

20. The opposite side 21 of the arm 16 is somewhat rounded to improve the action of the wrench.

Between the straight sides 18 of each arm and the curved side 21 of the next adjacent arm is placed a roller 22 substantially the same width as the arms between which they lie. The arms 17 are substantially the same width as the head 11 and the round ends of the body 14 project beyond the faces 13. On one projecting end of the body 14 is placed a washer 23 provided with a knurl 24 preferably in the form of arrows indicating the direction in which the wrench will drive a nut 25. On the opposite side of the wrench head and upon the other projecting end of the body 14 is placed a second washer 26 provided with arrows 27 pointing in the opposite direction than do the arrows 24, and, of course, indicating the manner in which the wrench will drive when reversed, so that the knurl 27 will be visible to the eye of the operator. The washers 23 and 26 are held in position by means of the rivet 28, which also passes through the hole 29 in one of the arms 16.

The operation of this wrench is, of course, similar to the ordinary ratchet wrenches, except in the important advantages which arise from its use, namely that there is no lost motion and it is easily possible for the operator to tell at a glance the direction in which the wrench will drive, in addition to the fact that he will be able to resist any backward rotation by the mere pressure of his finger.

While in Figure 8 there is shown the application of the wrench to a square nut, it will of course be understood that in ordinary practice it will be used in connection with a square bar on whose head is placed a socket of the desired size, making the wrench adaptable to any size of nut. Also if a square turning bar is not employed, but a hexagonal one is used instead, the opening 15 would be shaped accordingly. In some instances it might be desirable to provide a hinged handle instead of a rigid handle (as shown), or the handle itself may be slightly off-set, but these expedients are understood by those versed

in the art of wrench making and are therefore not illustrated or described.

I am aware that many forms of ratchet wrenches have been constructed in the past; it is therefore not my intention to cover such devices broadly, but I do intend to cover all such forms and modifications thereof as fall fairly within the appended claims.

I claim:

- 10 1. A ratchet wrench having a handle member provided with a cylindrical opening, a socket rotatably mounted within said opening having inclined faces formed around the periphery thereof, a wedging roller mounted on each of said inclined faces provided with spring means for normally urging same into a wedging position, the ends of said socket projecting from the sides of the handle, and a washer on each projecting end having a knurled surface on the outer side thereof indicating the driving direction of the wrench.
- 15 2. A ratchet wrench having a socket adapted to engage an object to be rotated, and having a disk mounted on each end of said wrench provided with a knurled surface indicating the direction in which said wrench can rotate said object.

GILBERT H. GROVES.
